UNITED STATES PATENT OFFICE.

GEORGE EDWARD HEYL-DIA, OF STRATTON, ENGLAND.

EXHIBITING MACHINE.

No. 908,668.

Specification of Letters Patent.

Patented Jan. 5, 1909.

Application filed April 29, 1905. Serial No. 258,137.

To all whom it may concern:

Be it known that I, GEORGE EDWARD HEYL-DIA, a subject of the King of Great Britain, and a resident of Stratton, near 5 Warrington, England, have invented certain new and useful improvements in Exhibiting Machines, of which the following is a specification.

The present invention relates to an exhibiting machine adapted to cause a picture, writing or other visual matter to be so exhibited as to be seen by a large number of persons.

In the drawings hereto annexed, I have 15 shown my invention in connection with a stock ticker, but I wish it to be understood that I do not so limit my invention to the particular application which, for the purpose of illustration, I have delineated, as it may 20 be used for a variety of purposes, such as the publication of news bulletins, by newspapers, the exhibition of advertisements, pictures and the like.

This invention consists in the construction, combination and arrangement of parts 25 set forth in and falling within the scope of the appended claims.

I will now proceed to describe my invention, as it is shown in the drawings, that is 30 to say, in connection with a ticker instrument.

The present ticker renders it necessary for persons to stoop over the instrument, and frequently grasp the thin paper strip, to ascertain 35 the quotations and prices recorded, and the like. Consequently but few persons can have access to and read the record at the same time. It is my purpose to provide means whereby the writing upon the 40 strip, as it leaves the instrument, will be thrown upon a wall or screen in magnified letters, thereby enabling the writing to be seen by all present.

In the accompanying drawings like characters of reference indicate like parts in all 45 the views, and Figure 1 is a view showing the application of the invention to a ticker; Fig. 2 is a view illustrating the means for guiding the strip, and feeding the same in 50 synchronism with the ticker; Fig. 3 is a side view of a portion of the tape feeding mechanism. Fig. 3^a is an edge view of the same. Fig. 4 is a detail view of the strip or tape 55 employed, which strip in use is of a transparent nature.

Referring to the accompanying drawings

in detail, A is an ordinary ticker having the usual printing wheel a, the bearing plate a' and the inking wheel a², the printing wheel being adapted to print characters upon the strip or tape B in a manner readily understood. In the present case in order to have the printing appear in proper position when thrown upon the screen, it will be necessary to place positive type upon the printing 65 wheel a.

For the purpose of my invention I make the tape B of transparent material upon which tape is applied printing matter b by means of the printing device. Upon leaving 70 the tape roll C of the ticker instrument, the strip is first guided between the spur wheel D and the bearing roller D', which latter is preferably formed with the spring tension arm d' and is secured at d' to the side of the 75 ticker mechanism. The spur wheel D in the course of its revolution feeds the strip along and between the printing wheel a and the bearing plate a' from whence the strip passes to the slide guide E forming a part of the 80 magnifying instrument F, which instrument may be in the form of an ordinary stereopticon. In its passage to the guide the strip is turned to a vertical position, as shown in Fig. 1, and after passing through such guide, 85 is directed over and around the roller G supported by an arm g to the side of the magnifying instrument F, such tape thence passing back toward the instrument and to the spring tensioned bearing roller H which 90 tends to hold or thrust the strip into contact with the spur wheel D, so that such wheel will tend to pull or feed the strip over the roller H and the strip may then be permitted to drop into any suitable receptacle, not 95 shown. By reason of the action of roller H the tape is maintained at an even tension during its travel from the feeding wheel D past the printing wheel and through the magnifying device, and its return to the under side of wheel D.

As will be seen by reference to Fig. 3, the tension roller H is formed with a groove h extending around the periphery thereof and such roller is journaled in a bifurcated arm 105 I, which arm is mounted in a small bracket J adapted to be secured to the side of the ticker.

K is the tension spring for thrusting or holding the roller against the spur wheel D.

From the above description taken in connection with the accompanying drawings the

operation of the device will be readily apparent.

When the ticker is in operation the transparent tape is fed past the spur wheel to the printing devices and after the quotations, or other matter, have been printed thereon the tape travels through the guide slide in a vertical position and the characters on such strip or tape are, through the medium of the magnifying device, projected or thrown onto the screen or wall in such manner as to be easily read by those present.

It will be noted that the device for feeding the strip works in synchronism with the ticker itself, being dependent upon the same actuating mechanism.

Having thus described my invention, what I claim and desire to secure by Letters Patent is:

1. The combination of a ticker instrument, including printing mechanism, a tape reel, a magnifying device, means for feeding the tape from the reel to a position to be operated upon by the printing mechanism, and

for feeding the tape through said magnifying device, said means to maintain the tape at an even tension during the feeding operation.

2. The combination of a ticker instrument including printing mechanism, and a tape reel, means for feeding the tape from the reel to the printing mechanism, such means including a spur wheel, and a bearing roller holding the tape in contact with the upper portion of the spur wheel, a magnifying apparatus, a guide formed on such apparatus for guiding such tape, a support for said tape after passing through the guide, and means for drawing said tape through the guide, such means including a tension device holding the tape in contact with the spur wheel.

In testimony whereof I have signed my name to this specification in the presence of two subscribing witnesses.

GEORGE EDWARD HEYL-DIA.
